(57) **CLAIM**

We claim the ornamental design for a partition insert, as shown described.

DESCRIPTION

FIG. 1 is a perspective view of a partition insert, embodying our design;

FIG. 2 is a front view of FIG. 1;

FIG. 3 is a side view of FIG. 1, the opposite side being a mirror image thereof;

FIG. 4 is a cross-section taken along lines 4—4 in FIG. 2, the cross-section showing the contour of surfaces in FIG. 2; FIG. 5 is a top view of FIG. 1, the bottom view being a mirror image thereof; and,

FIG. 6 is a cross-section taken along lines 6—6 in FIG. 2, showing the contour of surfaces in FIG. 2.

The dashed lines are to show the environment and do not form a part of the present invention.
